UNITED STATES PATENT OFFICE.

BENJAMIN FRANKLIN WALDRON, OF DUNCAN, OKLAHOMA.

UNDERREAMER.

Application filed April 28, 1925. Serial No. 26,494.

The present invention has reference to devices known as underreamers employed in connection with well drilling machinery to underream or cut the bore holed below the well casing to permit the well casing to pass into the bore hole.

An important object of the invention is to provide a device of this character including pivoted jaws adapted to be expanded 10 after they have passed the lower end of the well casing or lining, to underream the bore hole.

A still further object of the invention is to provide means whereby the underreamer 15 may be easily and readily withdrawn from its position within the well casing or lining after it has accomplished its purpose.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawings:

30 Figure 1 is a longitudinal sectional view through an underreamer constructed in accordance with the present invention, the lower portion of the reamer being shown in elevation.

35 Figure 2 is a sectional view taken on line 2—2 of Figure 4.

Figure 3 is a sectional view taken on line 3—3 of Figure 1.

Figure 4 is an enlarged sectional view of 40 the lower portion of the underreamer.

Figure 5 is a fragmental sectional view of a portion of the underreamer in its inactive position.

45 Referring to the drawings in detail, the reference character 5 indicates the well casting or lining through which the underreamer is passed when moved to its active position.

The reference character 6 indicates the 50 body portion or stock of the reamer which is hollowed out to accommodate the coupling 7 which is provided with a tapered threaded opening 8 at its upper end to accommodate the threaded extension 9 of the rod section 55 10 positioned thereabove.

The coupling 7 is formed with a longi-

tudinal bore the upper extremity of which being threaded to accommodate the threaded portion 11 of the rod 12, the lower end of the rod 12 being provided with an enlargement 60 13 formed with a shoulder 14 providing a seat for the lower extremity of the coiled spring 15 that acts to normally urge the jaws and jaw supporting rod, to be herein-after more fully described, downwardly. 65

The body portion 6 is formed with a central enlarged bore 16 in which the coiled spring 15 is positioned, there being provided a shoulder 17 at the upper end of the enlarged bore 16 against which the upper end 70 of the coiled spring 15 abuts. Thus it will be seen that due to this construction, the coupling together with the rod 12 may move upwardly against the tension of the coiled spring 15 which spring returns the rod to 75 its active position.

Lateral cut out portions are formed in the body portion 6, to accommodate the locking fingers 18 and their supporting blocks 19 which are formed with upper and lower extensions 20 provided with cut out portions 21 to accommodate the coiled springs 22 that bear against the upwardly extended flange 23 and downwardly extended flange 24 respectively, to the end that the supporting blocks 19 are normally urged outwardly. 80

Each of the supporting blocks 19 is formed with a cut out portion 24 formed in its inner edge which openings are formed with circular portions to accommodate the heads 25 of the locking fingers 18 so that the locking fingers may swing within the cut out portions to accomplish the purpose of the locking fingers to be herein-after more 90 fully described. 95

Communicating with the cut out portions 24 are bores 26 that are disposed at oblique angles with respect to the outer surfaces of the blocks 19 to permit an elongated tool to be inserted in the cut out portions 24 for engagement with the fingers 18 to move them to their active positions. Coiled springs 27 are positioned around portions of the heads 25, the ends thereof being in engagement with the fingers 18 to normally urge them to their inactive positions or out of contact with the groove 28 formed in the enlargement 13. 100

The groove 28 is formed with a shoulder 29 that is adapted to be engaged by the upper edges of the fingers 18 to hold the rod 12 and jaws supported at the lower end 110

thereof, to their inactive positions to allow the underreamer to be slid through the well tubing or lining.

The lower end of the rod 12 is tapered at 5 30 and is adapted to operate within the cut out portions 31 of the blades 32, the cut out portions 31 being disposed at oblique angles with respect to the body portion 6, the lower walls of the cut out portions 31 being inclined at 31' to present cam surfaces over 10 which the tapered end 30 of the rod may move to force the blades outwardly.

Threaded openings 33 are provided in the body portion 6 adjacent to the lower end 15 thereof, which openings accommodate the bearing members 34 that are also formed with threaded portions 35.

These bearing members 34 extend into openings formed in the blades 32 and act as 20 supports for the blades to allow the blades to pivot within the body portion 6 under the action of the rod 12. It might be further stated that the upper ends of the blades 32 are cut away at 36 providing clearances 25 to allow the blades to swing in a manner as described.

In order that the blocks 19 may be removably supported within the cut out portions 30 of the body portion 6, securing plates 37 are provided which securing plates engage the extensions 20 of the block to restrict outward movement of the block. Screws 38 extend through the securing plates and are embedded in suitable openings in the body 35 portion 6.

The upper outer edges of the blocks 19 are inclined as at 39 to provide cam surfaces to be engaged by the lower end of the well casing through which the device operates, when an upward pull is directed to the rod 12, to the end that the blocks 19 are cammed inwardly and drawn into the well casing to remove the reamer from the well casing.

45 In the operation of the device, the rod 12 is drawn upwardly until the blades 32 lie

within the body portion. A suitable tool is now positioned in the bores 26 and the locking fingers 18 pressed downwardly to engage the shoulder 29 of the groove 28 locking the rod 12 in its uppermost position, at the same time moving the blades 32 to their inactive positions.

When the reamer reaches the end of the well casing and the blocks 19 thereof pass 55 through the end of the casing, the spring member 22 acts to move the blocks 19 outwardly disconnecting the fingers, to the end that the blades drop downwardly and move to their active positions.

60 After the reaming operation has been completed, an upward movement on the rod 12 will cause the blocks 19 to be moved inwardly and the reamer withdrawn from the well casing. It will be seen that an underreamer of this character provides for the pivotal movement of the blades instead of a reciprocating movement thereof to the end that the blades will not become loosened 65 from their support and fall into the well. 70

I claim:

In an underreamer, a tubular body, said tubular body having lateral openings, laterally movable blocks supported within the openings, coiled springs for normally moving the blocks outwardly, pivoted fingers carried by the blocks, a vertically movable rod having a groove defining a shoulder, movable within the body, said fingers adapted to engage the shoulder to hold the rod in 75 an elevated position, pivoted blades having enlargements at their ends, said rod adapted to engage the enlargements to lock the blades in their active positions, at the end of the tubular member, and said blocks adapted to 80 move laterally to disengage the fingers and shoulder, and means for returning the rod to its initial position.

85 In testimony that I claim the foregoing as my own, I have hereto affixed my signature.

BENJAMIN FRANKLIN WALDRON.
